CLAIM

The ornamental design for a battery pack for a portable defibrillator, as shown and described.

DESCRIPTION

FIG. 1 is a front perspective view of a battery pack for a portable defibrillation showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

*Fig. 1.**Fig. 2.**Fig. 3.**Fig. 4.*

*Fig. 5.**Fig. 6.**Fig. 7.*
